UNITED STATES PATENT OFFICE

2,564,031

AUTOMOBILE AND WINDOW WASHER

Lloyd R. Rich, Hayward, Calif.

Application December 13, 1947, Serial No. 791,599

2 Claims. (Cl. 15—128)

1
This invention relates to improvements in means for washing automotive vehicles, windows, and the like, and provides a novel washer to be operated by hand, in remote relation to the object being washed, and in which the supply of water is under constant control, so that the clothing of the person operating the device will not be subjected to splash or spray of water.

It also provides a novel brush or washing element which can be removed or replaced at will, one which is easily applied or removed, and to which water is delivered directly and in which the pressure of the water is relieved to maintain a substantially constant pressure irrespective of the volume of water delivered.

The washing element is encased over a flexible head member to prevent marring and to permit the washing element to conform to the shape or curvature of the surfaces being washed.

Automotive bodies are conventionally washed with sponges or rags, holding a hose in one hand while operating the sponge or rag with the other. This requires that the person doing the washing must stand close with his clothing exposed to the flow, splash and spray, and when the water is exceptionally cold, the hands are subjected to practically freezing temperatures continuously.

With my invention it is never necessary to get the hands or clothing wet, so that car washing can be carried out relatively comfortably irrespective of the temperature of the water, and, if desired, hot water can as readily be used where a supply is available.

The objects and advantages of the invention are as follows:

First, to provide a remote control device for washing automotive bodies and the like.

Second, to provide a device as outlined in which water is delivered directly to the washing device.

Third, to provide a device as outlined in which the supply of water is under constant control, so as to limit delivery to the most desirable flow.

Fourth, to provide a device as outlined with a flexible head to prevent marring of the surfaces being cleaned.

Fifth, to provide a device as outlined with a flexible head provided with passages to relieve the pressure between the head and the washing element.

Sixth, to provide a device as outlined with an easily replaceable washing member to be supported on the flexible head.

Seventh, to provide the washing member with small apertures to pass water in restricted amount through the washing member for direct applica-

tion while passing additional water freely through the passages in the head to overflow to provide a rinse for the surface about the washing member.

5 Eighth, to provide a device as outlined which is simple in construction and economical to manufacture.

In describing the invention reference will be made to the accompanying drawings, in which:

10 Fig. 1 is a side elevation of the invention.

Fig. 2 is an enlarged fragmentary sectional elevation through the brush and head.

Fig. 3 is an enlarged bottom view of the flexible head.

15 The invention includes a conduit 10 which simultaneously functions as a handle and which may be of any desired length, about three to four feet being most desirable for automobile washing, and is preferably formed of aluminum, a magnesium-aluminum alloy or of suitable plastic material, and is curved at one end as indicated at 11 to form the head portion 12 at right angles to the handle portion 10. This head portion is flared out as indicated at 13, and to which the

20 flexible head 14 is attached and which is made considerably larger in diameter than the flange 13 so as to extend therebeyond. This head is formed of any suitable flexible material, such as live rubber, rubber or leather belting, or a flexible plastic, a vinyl resin plastic or rubber being particularly suitable for the purpose, and this head is provided with a plurality of equally spaced passages 15 to relieve the water pressure

25 within the washing element and provide an overflow over the top to provide a rinse for the surface washed. This head may be secured to the flange 13 by any suitable means such as by means of rivets 16.

30 Attached to the end of the handle portion is a valve 17 with integral handle 18 to which a hose 19 is attachable and which in turn is connectable to a suitable source of either hot or cold water as may be desired, and this valve is preferably of the pushbutton type, having a button 20 depression of which opens the valve, and

35 45 instead of the conventional cumbersome lever, for ease of operation and minimum span for the fingers of the user, and for lightness, a leaf spring 21 is secured at one end to the valve housing as indicated at 22 under just sufficient tension to keep the spring against the button and to return to its initial position when released.

40 The handle permits a finger to grip within the recess 23 without interference when the spring lever is depressed, with another finger controlling 45 the valve.

The washing element 24 is preferably formed of thoroughly cleaned sheep pelt of sufficient area to extend around the edges of the head as indicated at 25 and is provided with a multiplicity of fine apertures 26 through the skin so that water will flow and distribute through the wool 21 and keep it saturated and provided with excess flow under the brush as washing is carried out, and a section of fabric 28 is attached to the peripheral edges of the pelt leather and has a tunnel 29 formed at its free end through which a draw string 30 is threaded.

These brushes are attached by opening the gathered inside of the fabric heading and seating the head 14 therein, and drawing up and tying the draw string 30.

When washing a surface, the hose 19 is supplied with water under pressure, one hand grasps the handle 18 with finger control of the lever 21, and the other hand may grip the handle portion 10 of the conduit.

Depression of the lever 21 depresses the plunger 20 allowing water to flow through the conduit to the space between the pelt skin 31 and the head 14. This water with small supply forces the skin away from the head and the water passes through the apertures 26 and thence is distributed and passes through the wool, practically none reaching the passages 15 because of the pressure applied on the brush 24. With a greater supply, the skin also leaves the head at the passages 15, water still passing through the apertures 26 and distributing through the wool, with the excess passing through the passages 15 and over the top of the gathered tunnel to flow thereover and over the sides of the brush to rinse the area washed. Thus washing alone, or washing with simultaneous rinsing is under continuous control by the hand grasping the handle 18, and the supply can be regulated to suit the specific condition or requirement.

I claim:

1. A washing device comprising: a hood type washing element formed of sheep pelt; a circular head formed of flexible material and having said washing element removably secured thereon and having an axial water inlet passage, and a plurality of apertures formed therethrough in laterally spaced relation to said water inlet passage to relieve water pressure between the flexible head and the washing element to prevent warping of

the flexible head under pressure of water to prevent release of the washing element, and for overflow of excess water from the space between the washing element and the head to the top side of the head and over the head and sides of the washing element to serve as a rinse for the surface being washed; said sheep pelt having a multiplicity of spaced fine apertures formed through the skin thereof to diffuse water through the sheep pelt for continuous cleansing.

2. A washing device comprising: a conduit having a flared end forming a flange; a head formed of flexible material and circular in form and having a central passage communicating with said conduit; said head being fixed to said flange; a plurality of escape passages formed through said flexible head substantially midway between the peripheries of said head and said flange; a hood of sheep pelt removably secured over the underside of said flexible head and about the periphery thereof and having a multiplicity of tiny passages formed through the skin thereof to diffuse water through the wool of the pelt for continuous cleansing; said escape passages communicating between the inside of said hood and the top of the flexible head to relieve pressure to prevent warping of the flexible head under said pressure with consequent forcing of the hood off of the flexible head, and to provide a continuous rinse bath over the top and periphery of the hood.
